UNITED STATES PATENT OFFICE.

CLAUDE NELSON, OF PUEBLO, COLORADO.

SWITCH-STAND-HANDLE LOCK.

Application filed August 7, 1925. Serial No. 48,851.

To all whom it may concern:

Be it known that I, CLAUDE NELSON, a citizen of the United States, residing at Pueblo, in the county of Pueblo and State 5 of Colorado, have invented new and useful Improvements in Switch-Stand-Handle Locks, of which the following is a specification.

This invention relates to a railroad apparatus, particularly to switchstands and has for its object the provision of a novel locking device designed for use in holding the handle against accidental movement.

It is well known that the ordinary type of 15 switchstand supporting a rotatable shaft for throwing switch mechanisms is provided with an operating lever which depends, when in normal or inoperative position, and which is engaged within a notch in a guide 20 plate. Ordinarily, there is provided means for attaching a padlock whereby to hold the handle in position and prevent it from accidentally springing out of the notch within 25 which it is engaged. Switchmen very frequently neglect or forget to replace the lock and as a consequence the jarring of a 30 passing train may cause the handle to jump out of the notch with the possible result that the switch is opened and a serious derailment caused.

It is with the above facts in view that I have designed the present invention which has for its object the provision of a very simply and easily operated latch or lock device 35 permanently mounted upon the switch stand and cooperating with the handle for the purpose of holding the latter in its locked position within a notch in the guide plate so that it cannot possibly become accidentally displaced.

An important object is the provision of a device of this character which may be applied either to old or new style switchstands by making certain slight modifications.

Another object is the provision of a device 45 of this character which is so constructed and arranged that it may be easily operated in the dark or in cold weather when brakemen and switchmen wear thick clumsy gloves 50 which would interfere seriously with the manipulation of padlocks and the like.

An additional object is the provision of a device of this character which will be simple and inexpensive to manufacture, easy to install, positive in action, efficient and durable 55

in service, and a general improvement in the art.

With the above and other objects and advantages in view, the invention consists in the details of construction and arrangement 60 of parts to be hereinafter more fully described and claimed, and illustrated in the accompanying drawings, in which:—

Figure 1 is a side elevation of a portion of a switchstand and handle thereon, my invention being shown in applied position.

Figure 2 is a vertical section therethrough, the release position of the locking device and the operative position of the handle being shown by dotted lines.

Figure 3 is a plan view.

Figure 4 is a detail perspective view of the attachment alone.

Figure 5 is a side elevation of a portion of a switchstand of the old style showing the 75 application of the invention thereto, and

Figure 6 is a top plan view thereof.

Referring more particularly to the drawings and especially Figures 1 to 4, the letter A designates a portion of a switchstand having the usual guide plate B provided at its periphery with notches C and D within either of which may be engaged the handle E which is pivoted at F within a bracket G secured upon the vertical shaft H provided 80 for operating the switch throwing mechanism, not shown. As is well known, the handle E is provided with an apertured ear I within which is ordinarily engaged the shackle of a padlock provided for the purpose of holding the handle E down and preventing it from being moved upwardly into switch throwing position.

In carrying out the present invention, I provide a latching or locking device which 95 in actual practice may consist of a block 10 of suitable material located within the bracket device G and pivoted thereto near one end as for instance by means of a transverse bolt 11 or the like. One end of this 100 block is preferably bevelled off or cut-away as indicated at 12 so as to permit it to swing to a limited extent before coming into contact with that portion of the bracket G secured to the shaft H. Extending through 105 the opposite corner of the block is an operating means which may preferably consist of an elongated rod 13 movable along arcuate slots 14 formed in the sides of the bracket G as clearly indicated in the draw- 110

ings. Both ends of this rod 13 project beyond the bracket G and either end may be grasped for the purpose of lifting the block 10 and swinging it upon its pivot 11 out of the way of the lever E so that the latter may be swung upwardly into the switch throwing position as indicated by dotted lines in Figure 2. Subsequent to the movement of the locking block into its released position 10 shown by dotted lines in Figure 2, and upward swinging movement of the lever or handle E, the handle may be turned to rotate the shaft H and subsequent to the turning movement through an arc of 90 degrees 15 the handle is permitted to engage within the other one of the notches C or D, as the case may be. However, the present invention is not concerned with the switch throwing mechanism or the operation of any of the 20 parts thereof inasmuch as it relates only to the locking device constituted by the parts 10 to 14 inclusive.

The above described mechanism is that used in connection with switchstands of the 25 modern or new style although as a matter of fact the invention is equally well capable of application to switchstands of the old style as indicated in Figures 5 and 6. Referring to these figures, I have shown exactly 30 the same locking device 10 equipped with the operating rod 13. However, in this form the pivot bolt 11 above referred to is omitted and is replaced by a hinge indicated at 15, which has one leaf secured to 35 the block 10 and pivoted between knuckles J on the stand, the hinge having its other leaf 16 upturned so as to constitute a stop engageable with a portion of the shaft H or operating element thereon for the purpose 40 of limiting the swinging movement of the block. The operation of this form is of course exactly the same as that of the first described form and a further elaboration is consequently believed to be unnecessary.

In both forms of the invention, it will be apparent that when the switch is in one 45 position or the other, and the handle E depending and in engagement with a notch C or D, as the case may be, with the block resting against the handle, it will be quite 50 impossible for the handle to be moved out of engagement within its retaining notch unless the holding block is first swung upwardly into its released position. Obviously, 55 this will result in reduction of likelihood of accidents inasmuch as the jarring of a passing train cannot cause the lever to jump out of the notch as may occur in case the device is not used. Another point of 60 advantage is that when the block has been swung upwardly out of engagement with the lever, it will automatically drop into its locking position when released, no man-

ual manipulation being required to effect the holding. Another distinct feature of 65 importance is that the rod members which extend through and which project beyond the sides of the holding block may be easily grasped even though the brakeman or switchman is wearing heavy clumsy mittens 70 which might operate seriously with the manipulation of padlocks or other holding means commonly provided.

From the foregoing description and a study of the drawings, it will be apparent 75 that I have thus provided a simply constructed, inexpensive and highly efficient device for the purpose specified which will be a great safe-guard to the travelling public and which will reduce likelihood of derailment owing to carelessness or the inefficiency 80 of operators.

While I have shown and described the preferred embodiment of the invention, it should be understood that I reserve the right 85 to make such changes in the form, construction and arrangement of parts as will not depart from the spirit of the invention or the scope of the subjoined claims.

Having thus described the invention, I 90 claim:

1. In a switchstand including a support and an operating shaft journaled therethrough and further including a bracket member secured to the shaft and carrying a pivotally mounted operating handle, the combination with the bracket and handle of locking means pivotally mounted upon the bracket and normally engaging against the handle for holding the latter against movement, said holding means comprising a block pivoted at one corner within the confines of the bracket and having its free end normally in the path of travel of the handle, means carried by the block for effecting movement thereof into released position, the sides of the bracket being formed with arcuate slots permitting operation of the operating member.

2. In combination with a railroad switchstand having a normally depending pivotally mounted operating handle connected with a bracket, means mounted within the bracket normally holding the handle against movement comprising a block pivotally mounted at one end within the bracket and having its other end normally in the path of travel of the handle, a rod extending transversely through the free end of the block and serving as a handle, the rod projecting through arcuate slots in both sides of the bracket and projecting outwardly and beyond the same.

In testimony whereof I affix my signature.

CLAUDE NELSON.
